PUMP

Burt C. Williamson, La Verne, Calif.

Application August 9, 1935, Serial No. 35,541

12 Claims. (Cl. 103—46)

This invention relates to pumps and more particularly to a pump which is especially constructed for installation and operation in deep wells having small bores or holes where a pump occupying a minimum amount of space is necessary.

One of the principal objects of this invention is the production of a simple and efficient pump wherein one of the pistons or buckets is operated hydraulically simultaneously with the operation of a mechanically operated piston or bucket.

Another object of this invention is the production of a simple and efficient pump wherein the liquid lifting pistons or buckets mounted in the casing are actuated hydraulically.

A still further object of this invention is the production of an efficient apparatus for elevating liquid by means of a suction pump whereby the liquid is elevated first through pushing action of the piston or bucket upon the liquid to force the liquid above the piston, and then the liquid is lifted by the piston upon its upstroke.

Other objects and advantages of the present invention will appear throughout the following specification and claims.

In the drawings:

Figure 1 is a vertical section through the casing of the pump showing the pistons or buckets on the down stroke;

Figure 2 is an enlarged sectional view of the upper end of the casing and upper piston or bucket;

Figure 3 is a transverse section taken on line 3—3 of Figure 2;

Figure 4 is an enlarged vertical sectional view of the casing showing the hydraulically operated piston on its down stroke;

Figure 5 is a vertical sectional view similar to Figure 1 through the casing showing the parts on the up or discharge stroke;

Figure 6 is an enlarged vertical section through the casing showing the hydraulically operated piston or bucket on the up or discharge stroke;

Figure 7 is a vertical section through the casing showing the pistons or buckets operated hydraulically, the parts being shown in their down stroke position;

Figure 8 is a vertical section through the casing, certain parts being shown in elevation and the parts being shown in their up stroke or discharge position;

Figure 9 is a vertical sectional view of a further modified form of the hydraulically operated pump, showing the buckets in the down-stroke position;

Figure 10 is a similar view showing the buckets in the up-stroke position; and

Figure 11 is a vertical section through a modified form of the pump showing a pair of booster pumps connected to the by-pass pipes for passing the pressure around the piston rod.

By referring to the drawings, it will be seen that 15 designates the outer casing which is preferably of an elongated tubular structure of sufficient length to fit within the well 16. This tubular casing 15 is preferably closed at its upper end, as indicated at 17, and is provided with a discharge spout 18 which extends laterally from the upper end of the casing 15. The lower end 19 of the casing is open and is braced by means 15 of suitable radiating ribs 20 which ribs support in the center thereof an upstanding internally threaded socket 21 (note the enlarged detail in Figure 6).

A tubular barrel 22 is mounted within the outer casing 15 and fits snugly within the casing 15, as shown in Figures 1 and 5. This tubular barrel 22 is adapted to rest at its lower end upon an annular shoulder 23 formed near the bottom of the casing 15 and the barrel 22 carries at its lower end a plurality of converging depending arms 24 which carry an externally threaded stud 25, the stud 25 being adapted to be threaded into the socket 21 for anchoring the lower end of the barrel 22 in a resting position upon the annular flange 23.

An enlarged externally threaded pipe 26 is mounted in the upper end of the casing 15 and carries at its lower end a pair of laterally extending lugs 27 which lugs 27 travel between 35 the spaced track flanges 28 formed upon the inner face and at the upper end of the barrel 22. This arrangement will permit the enlarged pipe 26 to reciprocate within the barrel 22 and will also anchor the pipe 26 against independent 40 rotation within the barrel 22, thereby enabling the barrel 22 to be rotated with the pipe 26 to cause the threaded stud 25 to be seated within the threaded socket 21 for anchoring the barrel 22 in a set position upon the flange 23. This arrangement will permit the removal of the barrel 22 for repair or replacement without the necessity of removing the casing 15. Annular bearing rings 29 are threaded upon the enlarged pipe 26 and arranged in spaced relation to constitute a 50 bracing means for holding the pipe 26 in proper alignment and preventing the bending of the operating rods. The upper end of the pipe 26 carries a web 30 having an internally threaded socket 31 at its center for receiving the external-

ly threaded end of the mechanically operated rod 32, which rod 32 passes through the stuffing box 33 carried by the top 17 of the casing 15, and this operating rod 32 may be connected to any suitable or desired operating mechanism. It should be understood that the pipe 26 is of sufficient length and the parts may be of sufficient length to accomplish the desired results.

The lower end of the pipe 26 is provided with a web 34 having a centrally located internally threaded socket for receiving the externally threaded hollow pipe 36. A piston or bucket 37 is anchored upon this hollow pipe 36 and is preferably held in place through the medium of threaded collars 38. The piston or bucket 37 is preferably provided with a plurality of upwardly turned leather cups 39 of the conventional type which are anchored in engagement with the piston through the medium of securing bolts 40.

20 The piston or bucket 37 is provided with vertically extending ports 41 and flap valves 42 are carried by the top face of the piston or bucket 37 to permit the passage of liquid vertically through the ports 41 and to automatically close and seal the ports against a return downward flow. It should be understood that this bucket 37 or piston 37 is anchored to reciprocate and move with the threaded pipe 36 upon which the bucket or piston 37 is mounted.

30 A tube 43 is arranged to extend vertically in a centrally located position within the barrel 22 and this tube 43 is braced by means of the radiating bracing rods 44 which are secured to the tube 43 at spaced intervals and are also anchored in engagement with the inner face of the barrel 22. A stuffing box 45 is carried by the upper end of the tube 43 and a stuffing box 46 is carried by the lower end thereof (note Figures 2 and 4). The lower end of the hollow pipe 36 is reciprocably mounted within the upper end of the tube 43 and passes through the stuffing box 45. The lower end of the pipe 36 carries a plug 47, and a bleeder pipe 48 extends vertically through the plug 47 and communicates with the interior of the hollow pipe 36 to prevent the tube 43 from becoming air bound under the action of the reciprocating piston rod hereinafter described. The vertically extending bleeder pipe 48 is supported upon a partition 49 carried by the tube 43 in spaced relation to the limit of the downward stroke of the pipe 36, within the tube 43, as is shown in Figure 4.

40 A vertically extending plunger rod 50 is carried within the barrel 22 and the upper end of this plunger rod 50 is reciprocably mounted within the lower end of the tube 43, the lower end of the piston rod 50 being mounted within a lower tubular casing 51 which tubular casing carries a stuffing box 52 at its upper end to constitute a seal around the piston rod 50, as shown in Figure 4. The tube 43 is provided with a check valve 53 and a pop-off valve 54 for the purpose of safety, and the tubular casing 51 is provided with a check valve 55 and a pop-off safety valve 56 located near the limit of the up stroke of the piston rod 50 in the tube 43 and the tubular casing 51. A pair of by-pass pipes 57 form a communication between the interior of the tubing 43 just above the partition 49 in order to form a communication with the lower closed end 47 of the pipe 36 and the lower end of the tubular casing 51 below the bottom or lower end of the piston rod 50, as shown in Figure 4.

50 A piston 60 is anchored upon the piston rod 50 intermediate the tube 43 and the tubular cas-

ing 51 and carries a plurality of upturned leather cups 61. A plurality of ports 62 are formed in the piston 60 and these ports are closed against downward flow by the flap valves 63, which flap valves are readily opened to permit upward flow through the piston on its down stroke.

5 The operation of the device is as follows:—

Upon the downstroke of the operating rod 32 the pipe 26 will be forced downwardly carrying the piston 37 downwardly and this will open the 10 valves 42 and permit the passage of liquid up through the ports 41. As the piston 37 is moved downwardly the pipe 36 which is closed by the plug 47 at its lower end, will slide downwardly through the tube 43 and force the liquid which 15 is contained within the tube 43 down through the by-pass pipes 57 and into the lower end of the tubular casing 51. This liquid will act against the bottom end of the piston rod 50 thereby forcing the piston 60 upwardly to lift the liquid above 20 the piston 60 in an upward direction, the flap valves 63 at this time remaining closed. Upon the reverse stroke or up stroke, the piston 37 will move upwardly closing the valves 42 to prevent down flow through the ports 41 and the piston 25 60 will then move downwardly opening the flap valves 63 and permitting the flow of liquid through the ports 62 from a position below the piston or bucket 60 to a position above the piston or bucket 60. From the foregoing description it 30 will be seen that as the piston 37 moves downwardly, the piston 60 will move upwardly, and as the piston 37 moves upwardly, the piston 60 will move downwardly, these pistons 37 and 60 alternately moving toward and away from each 35 other on the respective alternating strokes of the operating rod 32.

It will be noted from the foregoing that the externally threaded enlarged pipe 26 will provide a wide bearing and brace from the upper 40 end of the operating rod to prevent bending. Furthermore, the structure as described will permit the interior mechanism to be entirely removed from the well without removing the well casing to permit repairs or replacement to be 45 made. Because of the structure described a minimum number of rods will be required for the operation of the pump, the actuation of the mechanically operated piston automatically causing the hydraulically operated piston to be actuated 50 thereby facilitating the flow of liquid out through the discharge spout 18. It should be understood that the present device is particularly adapted for use in pumping oil, water, or other liquids from wells, particularly that type of well where 55 the bore is necessarily small, and where the space for the operating mechanism is necessarily restricted.

60 In Figure 11 there is shown a modified form of the invention wherein a piston rod 50a is illustrated having laterally extending arms 64 to which are secured piston rods 65 for actuating pistons 66 mounted within the cylinder 67 constituting booster pumps which communicate, as at 68, with the by-pass pipes 57a similar to the by-pass pipes 57 previously described. These additional pistons may be employed for boosting the hydraulic pressure if this should be found necessary by injecting pressure in the pipes 57a intermediate the ends of the by-pass pipes, as well as 65 at the ends thereof. It should be understood that the structure shown in Figure 11 is an optional structure embodying a modification wherein the cylinders 67 which constitute booster pumps are secured to the piston rod 50a which 70 75

corresponds to the piston rod 50 shown in Figure 4, these booster pumps being adapted to be located in a position below the housing 43 and just above the limit of the upward stroke of the piston 60 illustrated in Figure 4. In Figures 7 and 8 there is shown a further embodiment or modified form of the present invention illustrating a double type of hydraulic piston, the structure previously described employing a single hydraulically operated piston and a mechanically operated piston. In the structure shown in Figures 7 and 8, a housing or casing 70 is illustrated carrying an upper tubular casing 71 and an intermediate tubular casing 72 and a bottom tubular casing 73. The upper tubular casing 71 is provided with an inlet pressure pipe 74 communicating with the upper extreme end of the casing 71 and a piston rod 75 is slidably mounted through the lower end of the casing 71. This piston rod 75 is also slidably mounted in the upper end of the intermediate casing 72, the intermediate casing 72 having a central partition 76 for providing an upper compartment 72a and a lower compartment 72b within the casing 72. A piston rod 77 has its upper end slidably mounted within the compartment 72b and the lower end of this rod 77 is reciprocably mounted within the upper end of the casing 73.

A pair of by-pass pipes 78 communicate with the lower compartment 72b of the casing 72 and a pair of by-pass pipes 79 form a communication between the upper compartment 72a of the casing 72 and the lower end of the casing 73 to act upon the lower end of the piston rod 77. This structure is illustrated in Figure 7. A piston 80 is anchored upon the piston rod 75 and is adapted to actuate therewith, the by-pass tubes 78 being slidably mounted through the piston 80 and this piston being provided with flap valves 81 similar to the valves carried by the piston 37 described in the first embodiment. The piston rod 77 also carries a lower piston 82 which is provided with valves 83 similar to the valves carried by the piston 60 described in the previous embodiment.

The operation of this structure just described, is as follows:—

Pressure enters the pipe 74 and forces the piston rod 75 downwardly, moving the piston 80 downwardly and allowing liquid to pass up through the valves 81. Hydraulic pressure within the compartment 72a will travel down through the by-pass tubes or pipes 79 and act upon the lower end of the piston rod 77 moving the piston 82 upwardly in a manner similar to that as described in the first embodiment. Upon the reversal of the pressure, the pressure will enter the pipes 78 and cause the parts to operate in a reverse manner spreading the pistons 80 and 82 apart on the respective alternate strokes. The casings 71, 72, and 73 are provided with suitable check valves to facilitate proper and safe operation. It should also be understood that any type of control mechanism may be employed for controlling the entrance of hydraulic pressure into, and the exhaust from, the pipes 74 and 78. From the structure shown in Figure 7 it will be observed that upon the direct operation of the piston 80 to produce a down stroke, the piston 82 will be actuated in a complementary manner through the passage of the hydraulic pressure through the by-pass pipes 79. Upon the return stroke, the pressure will pass down through the pipes 78 and act directly upon the piston 77 to operate the piston 82 and in this instance the piston 80 will act complementary with the piston 82 as a result of

the hydraulic pressure passing up through the pipes 79.

In the form shown in Figures 9 and 10 there is illustrated a structure for producing a hydraulically operated pump wherein 110 designates the well casing within which is mounted and spaced therefrom a special column joint 111 at the bottom of the water column 112. The pump cylinder 113 is mounted within the column 112, as shown, and is provided with an upper series of ports 114 and a lower series of ports 115 separated by a baffle plate or partition 116.

A plurality of buckets or pistons 117 having valves 118 are located in the upper compartment 119 and a plurality of buckets or pistons 120 having valves 121 are located in the lower compartment 122, the compartments 119 and 122 being formed by the partition 115. The pistons 117 and 120 carry plungers 123 and 124 respectively working in cylinders 125 and 126, the alternate cylinders being connected by the by-pass pipes 127, as shown in Figures 9 and 10.

The cylinder 113 is anchored in position by means of a threaded neck 127 fitting in a threaded socket 128 carried by the lower end of the column 111 and the lower end of the cylinder 113 abuts against the supporting shoulder or flange 129, as shown in Figures 9 and 10. Hydraulic pressure may be initially supplied from any source of controlled supply by admitting pressure through the upper by-pass pipes 127.

The operation of the structure shown in Figures 9 and 10 is as follows:—

On the down-stroke the liquid will pass up through the valves 121 in the bottom bucket and the liquid in the lower cylinder 126a will be forced up through the pipe 127a to the cylinder 126b. Hydraulic pressure will also pass from the cylinder 125a down through the pipe 127b to the cylinder 126c, the piston 120 being moved apart within the compartment 122 and the pistons 117 will be moved apart in the compartment 119. On the reverse movement, the pistons will be moved toward each other in this manner, providing the lifting action similar to that described in connection with the foregoing forms.

Communicating ports 130 are formed between the interior of the cylinder 113 and the exterior of the column 111, as shown in Figures 9 and 10. The structure illustrated in Figures 9 and 10 may be multiplied to provide as many compartments as may be desired without departing from the spirit of the invention.

Having described the invention, what is claimed as new is:—

1. A pump of the class described comprising a casing, a cylinder within said casing, a mechanically operated piston head operable within said cylinder, a piston rod supporting said piston head and extending below said head, a housing comprising a pair of non-communicating compartments adapted to contain hydraulic pressure, said piston rod fitting in one compartment, a second piston rod slidably mounted within the other compartment of said housing below said first mentioned piston rod, by-pass means forming a communication between the first mentioned compartment and the second mentioned compartment at a point below the second mentioned piston rod, a second piston head carried by said second piston rod and located below said first mentioned piston head within said casing, a second housing for receiving the opposite end of said second piston rod located below said first mentioned housing, by-pass tubes forming a com-

munication between said housings for transmitting hydraulic pressure from one housing to the other as said first mentioned piston rod is reciprocated, and valves formed in each piston for permitting the passage of liquid through the pistons in an upward direction as the pistons are reciprocated.

2. A pump of the class described comprising a casing, a cylinder within said casing, a mechanically operated piston head operable within said cylinder, a piston rod supporting said piston head and extending below said head, a housing comprising a pair of non-communicating compartments adapted to contain hydraulic pressure, said piston rod fitting in one compartment, a second piston rod slidably mounted within the other compartment of said housing below said first mentioned piston rod, by-pass means forming a communication between the first mentioned compartment and the second mentioned compartment at a point below the second mentioned piston rod, a second piston head carried by said second piston rod and located below said first mentioned piston head within said casing, a second housing for receiving the opposite end of said second piston rod located below said first mentioned housing, by-pass tubes forming a communication between said housings for transmitting hydraulic pressure from one housing to the other as said first mentioned piston rod is reciprocated, each piston having vertically extending ports, flap valves covering the ports for swinging upwardly to permit of the passage of liquid through the pistons in an upward direction and preventing the passage of liquid in a downward direction, and said by-pass tubes passing through said second piston.

3. A pump of the class described comprising an outer casing, a removable barrel snugly fitted within said outer casing, a mechanically operated piston slidably mounted within the barrel, a hydraulically operated piston snugly mounted within the barrel, hydraulic means actuated by the operation of said mechanically operated piston and in communication with said hydraulically operated piston below the hydraulically operated piston for simultaneously actuating the hydraulically operated piston, means for detachably anchoring the lower end of the said barrel within said casing, and means engaging the upper end of the barrel for facilitating the removal of the barrel from said casing.

4. A pump of the class described comprising an outer casing, a removable barrel snugly fitted within said outer casing, a mechanically operated piston slidably mounted within the barrel, a hydraulically operated piston snugly mounted within the barrel, hydraulic means actuated by the operation of said mechanically operated piston for simultaneously actuating the hydraulically operated piston, said hydraulic means having entrance and exit means below said hydraulically operated piston, means for detachably anchoring the lower end of said barrel within said casing, means engaging the upper end of the barrel for facilitating the removal of the barrel from said casing, said casing having an abutment shoulder for supporting the lower end of the barrel, said anchoring means comprising depending converging arms, and a threaded connection engaging the lower ends of said arms to provide anchoring means.

5. A pump of the class described comprising an outer casing having a discharge port at its upper end and an inlet at its bottom, a removable

cover, an operating rod extending through and operating through said cover, an enlarged operating pipe engaging said operating rod, friction rings carried by said pipe, a barrel snugly fitted within said casing, guiding lugs carried by the outer face of said pipe for permitting reciprocation of the pipe and preventing rotation of the pipe in the barrel, a piston slidably mounted within said casing and carried by said enlarged pipe and provided with ports and upwardly opening check valves therefor, a piston rod depending from said piston, a hydraulic housing supported within said barrel, said housing comprising a pair of non-communicating upper and lower compartments, said piston rod working within the upper compartment, a second piston working within said barrel and provided with ports and upwardly opening check valves therefor, a hydraulically operated piston rod carried by said second piston with its upper portion working within the lower compartment, a second hydraulic housing below said first mentioned casing, a piston rod suspended below said second piston and working within said second hydraulic housing, by-pass means communicating with the first mentioned compartment below the first mentioned piston rod and with the last mentioned hydraulic housing below the last mentioned piston rod, means for supplying hydraulic pressure to the second compartment for action against the second mentioned piston rod whereby the pistons may be caused to simultaneously operate in opposite directions as hydraulic pressure is applied and released, and a threaded anchoring means carried by the lower end of the barrel for securing the barrel in an anchored position.

6. A pump of the class described comprising an outer casing having an outlet at its top and an inlet at its bottom, a plurality of hydraulic housings within said casing and disposed one above the other, a piston slidably mounted within the casing and adapted to be reciprocated vertically through the action of hydraulic pressure forced into and out of said housings, the upper one of the housings having upper and lower non-communicating compartments, said piston having an upwardly extending piston rod and a downwardly extending piston rod, the upwardly extending piston rod working within the lower compartment of the housing and the downwardly extending piston rod working within the lower hydraulic housing, by-pass pipes establishing communication between the upper compartment of the upper housing and the lower hydraulic housing at a point below the lower end of the downwardly extending piston, and a working piston having a piston rod operating in the upper compartment of the upper housing for supplying and releasing hydraulic pressure to and from the lower housing and imparting reciprocating movement to the first piston.

7. A pump of the class described comprising an outer casing, upper and lower hydraulic housings within said casing, a piston slidably mounted within the casing and adapted to be reciprocated through the action of hydraulic pressure forced into and out of said housings, the upper one of the housings having upper and lower non-communicating compartments, said piston having an upwardly extending piston rod working within the lower compartment of the upper housing and a downwardly extending piston rod working within the lower hydraulic housing, by-pass pipes establishing communication between the upper compartment of the first mentioned hous-

ing and the lower hydraulic housing at a point below the lower end of the downwardly extending piston, means for supplying and releasing hydraulic pressure to and from the lower compartment of said first mentioned housing in and for the purpose specified, and pressure pumps operated by one of said piston rods and communicating with said by-pass pipes for boosting the hydraulic pressure within the by-pass pipes and 5 housings.

10. A pump of the class described comprising a casing having an upper outlet and a lower inlet, a plurality of hydraulic housings, a plurality of pistons slidably mounted upon said casing and 15 interposed between said housings, oppositely extending piston rods carried by each piston, a separate housing compartment for each oppositely extending piston rod, power operated means for initially controlling the admission and release 20 of hydraulic pressure to one housing compartment, by-pass means forming a communication with one housing compartment below the piston rod operating therein and a compartment of an adjoining housing above the piston rod operating therein whereby movement imparted to one piston rod will cause a relative movement of all of the piston rods by alternately applying and releasing pressure in and for the purpose specified.

9. A pump of the class described comprising 30 an outer casing, a column spaced therefrom having an inlet at its bottom, a cylinder mounted within said casing and open at its bottom, said cylinder being divided into a plurality of compartments, a plurality of hydraulically operated 35 pistons mounted within each compartment, hydraulic operating means having alternate communication above and below the alternate pistons to control the reciprocation of the pistons and cause successive pistons to move in opposite directions, and said cylinder having ports formed 40 therein for facilitating the passing of liquid from the lower compartment to the compartment just above and provided with upwardly opening check valves.

45. 10. A pump of the class described comprising an outer casing, a column mounted therein and spaced from the side walls of said casing and provided with a lower inlet and an upper outlet, a cylinder mounted within said column and spaced from said column, said cylinder and column having means forming a communication between the interior of the cylinder and the space between the casing and column, said cylinder having ports forming a communication between the interior and exterior of said cylinder, a partition for dividing said cylinder into a plurality of compartments, a plurality of spaced pistons mounted for reciprocating motion in each compartment, a plurality of non-communicating hydraulic housings mounted within each compartment one above the other, plungers carried by each piston and fitting within each hydraulic housing, each piston having valves formed therein, the alternate hydraulic housings having a by-pass pipe connection whereby said pistons will alternately move toward and away from each other as hydraulic pressure is increased and decreased in the respective cylinders and fluid forced upwardly in step-by-step movements as the pistons move upwardly, and means for ini-

5 tially supplying hydraulic pressure to the uppermost hydraulic housing, the by-pass pipe being connected to the next adjoining housing below the piston rod and to an adjoining housing above the piston rod whereby the movement of one piston rod downwardly will force the hydraulic pressure into the last mentioned housing and cause the corresponding piston to move downwardly and vice versa.

11. A pump of the class described comprising a 10 casing having a lower inlet and an upper outlet, a piston slidably mounted near one end of said casing and formed with ports having upwardly opening check valves, a piston rod suspended below said piston, a hydraulic housing comprising 15 a pair of non-communicating compartments one of which receives the lower end of said piston rod, a second piston slidably mounted within the other compartment of said housing below said first mentioned piston and formed with ports having 20 upwardly opening check valves, said second piston having piston rods extending above and below, a second hydraulic housing receiving the piston rod below the second piston, the piston rod above the second piston extending into the second 25 compartment of the first mentioned hydraulic housing, a by-pass establishing communication between the lower end of the first mentioned compartment under its piston rod and the upper end of the second mentioned compartment 30 of the first mentioned housing above its piston rod, and means for supplying and releasing hydraulic pressure to and from the first mentioned compartment of the first mentioned housing whereby said pistons may be simultaneously operated 35 in opposite directions and fluid moved upwardly above the pistons in step-by-step movements.

12. A pump of the class described comprising a 40 casing having a lower inlet and an upper outlet, a mechanically operated piston slidably mounted near one end of said casing and formed with ports controlled by upwardly opening check valves, a piston rod suspended below said piston, a hydraulic housing comprising upper and lower 45 non-communicating compartments located below said piston, the upper compartment receiving the lower end of said piston rod, a hydraulic piston slidably mounted within said casing below said first mentioned piston and formed with ports controlled by upwardly opening check valves, said 50 hydraulic piston having piston rods extending above and below, a second hydraulic housing receiving the piston rod below the second piston, the piston rod above the second hydraulic piston extending into the lower compartment of the first 55 mentioned hydraulic housing, means for supplying and releasing hydraulic pressure to and from the lower compartment of the first mentioned housing above its piston rod, and by-pass means 60 forming a communication between the upper compartment of the first mentioned housing and the second mentioned hydraulic housing at a point below its piston whereby said pistons may be actuated and moved towards and away from each other for forcing fluid upwardly through 65 the ports of the pistons and upwardly through the casing in step-by-step movements.
